NEW YORK

APPARATUS FOR RIVETING PLATES OF SHIPS

Application filed April 18, 1930. Serial No. 445,240.

The improvements relate primarily to means and methods of riveting the shell plates of steel ships, but are not limited to this specific use.

5 In the building of the steel ships the outside or shell plating is usually applied to the frame from the bottom up, one or more courses being applied to the frame and bolted in place and then riveted, the work progressing upwardly in this manner in successive stages.

10 In ships of great tonnage, wherein lapped and butt strapped steel plates an inch and a quarter or more in thickness may be employed, hydraulically squeezed rivets are used for the plates forming the upper part of the shell, where the greatest strength is required, rather than pneumatic or hand hammered rivets, and in applying these rivets a pressure as high as sixty tons or more is employed, the hot rivets being inserted through the rivet holes with the flange of the rivet head against the outer surface of one plate and the end to be upset or headed projecting beyond the opposite plate. A hydraulic "bull" riveter is then placed in position against one end of the hot rivet and a "holder-on" or anvil against the other end, and the hydraulic pressure applied until the rivet is squeezed or pressed home and headed up. Rivets in excess of an inch in diameter are commonly used for this purpose, and thorough tests and examination have demonstrated that greater and more uniform strength is ensured when the hydraulic squeezing method is employed, thus adding greatly to the factor of safety and durability.

15 When the plating is first applied to the frame in building up the hull a yoke is usually employed in the hydraulic method. This yoke consists of a substantially U-shaped rigid steel frame of great weight and strength which may be hung over the upper edges of the shell courses with its arms extending down on opposite sides of the plates, so that the yoke straddles the said plates. The hydraulic operated press or ram is mounted at the end of one arm of this yoke and the holder-on or anvil opposite it in alignment therewith on the end of the other arm, so that

when the riveter head and anvil are applied to opposite ends of a rivet and hydraulic pressure applied to the riveter, the rivet will be squeezed or pressed home between them and headed up on one side, the necessary backing 55 on both sides in this operation being provided by the two arms of the yoke.

The yoke riveter may be moved along the upper portion of the hull to drive or squeeze rows of rivets uniting the lapped edges of 60 two courses of plates or strakes and then raised and moved along to drive the next row of rivets. It may also be worked vertically to drive the rivets joining the strapped or lapped butts of the plates of a strake. 65

70 It will be seen that on account of the high pressure employed in this squeezing method, and the necessity of moving the yoke, there is a limit to the length of the yoke due to the fact that great mass and weight of metal must be employed to resist the stress imposed thereon by the pressure. Yokes commonly employed are limited to a length of approximately ten feet, and in this size will weigh 75 as much as seventeen tons or more. It will also be seen that in repairing and replacing the plates of a ship which has been damaged in collision or by heavy seas, or other causes, the employment of a yoke below decks is not possible without the removal of deck 80 stringers, a portion of the decks, the plates above those damaged and in some cases other parts, which would increase cost of the repairs enormously. Yet, as above noted, hydraulic squeezing of the rivets in ships of 85 great tonnage is required. The necessity for this will be understood when it is pointed out that steel plates one and one quarter inch or more in thickness are used and that the strength of these plates is no greater than the 90 strength and security of the riveted portions.

Nor is it practically possible to brace the riveter and holder-on against the frame of the ship, since this would subject such parts to a tremendous strain, which would not be a safe procedure, with the plates secured only by temporary bolts, and would also necessitate the removal of floors, partitions and other parts and would at the same time in 95 100

terfere greatly with the mobility of the riveting apparatus.

It is therefore to overcome these difficulties and to facilitate the work of riveting new plates, replacing those weakened or damaged without removing or injuring other parts of the ship that the present improvements are primarily designed. The method and appliances embodying the present improvements are not, however, limited to this particular application but may be used for other purposes to which they are adapted.

The improvements may be embodied in the appliances illustrated in the accompanying drawings, employed in the manner described, these appliances and this method of employing them being described and shown as an illustrative embodiment of the invention, but not as a limitation thereof, since it is obvious that various modifications thereof may be employed without departing from the scope of the invention.

In the said drawings, Figure 1 is a plan of a hydraulic riveting apparatus embodying the present structural improvements and adapted to be employed in practicing the present improved method or process;

Figure 2 is a vertical section of the same, looking in the direction indicated by the arrows in Figure 1;

Figure 3 is an elevation looking outboard or in the direction indicated by the arrow in Fig. 2.

The appliances illustrated in the drawings comprise a pair of steel plates 1 and 2 of heavy steel, reinforced and rendered rigid by integral heavy steel flanges 3, 3' and 4 respectively and straps 5 and 6 secured to said flanges and running across the same; connecting and adjusting rods 8 bolted through the plates 1 and 2 and spacing them; an anvil or holder-on 9 backing against the plate 1 and a hydraulic riveter 10 backing against the plate 2, both movable thereon; air rams 11 and 12 carried by the plates 1 and 2 respectively and spacing and adjusting stops 13 and 14 on one of the rods 8.

The plates 1 and 2 with their reinforcing members constitute what are called "strongbacks" to receive the pressure of the riveter, and the connecting rods are passed through the plates A to be riveted. For this purpose rivet holes may be taken advantage of, or other holes may be drilled through the plates. It is also possible to use port holes or any other openings in the hull, if convenient.

The rods 8 are preferably connected with the strongbacks by being passed through the rectangular plates 1 and 2 near their four corners, and are held against longitudinal movement and the plates held against movement thereon or with respect thereto by means of nuts 15 and 16 on opposite sides of the plates and on the threaded ends 8' of the rods. This arrangement permits the accu-

rate adjustment of the plates so that they will be disposed in planes exactly parallel to each other and held securely in this relation. This is important for the reason that if the plates were not so disposed the pressure caused by the hydraulic riveter would cause a twisting strain or torque on the plates and the rods, which would tend to distort these parts and also buckle the rods, and to cause them to bind in the holes of the plates through which they are intended to slide freely. Parallelism is also essential to proper squeezing and heading of the rivets. The rods number 3 in each group, and are arranged in line, but any other suitable number of rods and any other satisfactory arrangement may be employed. The rods may also be otherwise distributed and the plates may be of other size, form and construction, it being contemplated that the inside plate may be of small area, where the compartments in the hull are such that an inside strongback of the same size as the outside strongback cannot be conveniently used.

It has been found desirable to lubricate the rods and the holes in the plates in which they work with lubricating grease, so that they will slide freely therethrough and will not bind, but this is not essential, and any other means for preventing binding may be employed.

The entire structure including the strongbacks and connecting rods may be supported vertically in any suitable manner, as by slings or chains hung overhead or by blocks or rails placed beneath them and on which they may slide. This makes it possible to have the strongback and its support entirely between decks B and C, as indicated. In order to have the inboard back clear the deck beams D or other obstructions, it may be mortised at the top as shown at 17, 18 and 19, or otherwise shaped to clear them.

The holder-on 9 has its base 20 against the plate 1 of the inboard strongback and has its anvil shank 21 provided with a recess 22 to form a head on the rivet, in the usual manner. The riveter 10 has its base 23 against the plate 2 of the outer outboard strongback and also has its riveting punch or die 24 provided with the usual recess 25, to fit over the head of a rivet or form a rivet head, as the case may be. It also has the usual forward moving fluid pipe connection 26 and backing pipe connection 7. This riveter and the holder-on or anvil member may be of any desired form. As illustrated, the riveter is of the usual hydraulic plunger form used with the yoke type bull riveter and operates in the ordinary way, and therefore need not be further described. The details of construction of the holder-on are also unimportant, so long as the construction is such as to provide a sufficiently strong and rigid backing or anvil. Both members may

also be mounted on their plates in any suitable manner, so as to be moved in both directions thereon to operate on rows of rivets uniting lapped plates and similar rivets uniting the butts of the plates. As several laps of the plates will be operated on between each deck and the next, in some cases, it is necessary that the riveter and holder-on be movable substantially throughout the length and height of the backs. To this end they may be hung on chains suspended from any convenient overhead part or from the bars 8 (see F and G, Fig. 1) and provided with block and tackle, or other means for supporting these members and permitting horizontal and vertical movement may be used, such as beams mounted to slide up and down on which the riveter and holder-on may be mounted to slide horizontally. The stops 13 and 14 are employed when desired to limit and adjust the movement of the frame composed of the strongbacks and connecting bars by coming in contact with the plates A. They will not however be placed so that they will exert any substantial pressure against these plates, as such pressure might buckle the plates. Their principal function is to provide a guide which will enable the operators to ascertain that the backs are accurately spaced.

The air jamb or rams 11 and 12 are employed to move the backs in one direction or the other to push the rivet through its hole and dispense with the use of a sledge for that purpose. The ram 11 moves the backs in an inboard direction and the ram 12 moves them in an outboard direction, the first by pressing its plunger 11' against the inner side of the plates and the latter by pressing its plunger 12' against the outer side, so that the back in each case is moved away from the plates and the opposite back toward the plates. This movement brings one of the riveter dies in contact with the head of the rivet, and holds it in place until the hydraulic pressure is applied to squeeze and set the rivet. A rivet which has been thus squeezed, headed and set, is indicated at E (Fig. 2). When a rivet has been set, one of the air rams is operated again to move the strongback away from the plates and permit the insertion of another rivet. The riveting members are also moved to the next rivet hole after each squeezing operation.

It will be seen that the squeezing operation may be performed in the employment of the improvements in two ways, i. e., either by passing the rivet through the hole from the outside until its head is close to the outer surface of the plates and its unset shank projects on the opposite side and then pressing the riveter head against the head of the rivet 24', thus causing the anvil die 21 to move with the inboard back against the unset end of the rivet, or by inserting the rivet from the

inside, moving the anvil die against its head and then setting it by means of the riveter die or head 24. In the first method, the riveter 10 presses against the head of the rivet and forces the outboard back away from the plates and the inboard back carrying the holder-on 9 against the rivet, and in the second method the riveter head 24 simply squeezes the unset end of the rivet down while the headed end on the opposite side is held against the plate and also squeezed by the anvil die. In the first method the extending shank of the rivet is set by the die 22 and in the second method it is set by the riveter head or die 24. In both operations the head 24, which is the end of a plunger, is retracted while the rivet is being inserted, and in both operations the strongbacks are moved inboard or outboard after a rivet has been squeezed to permit the passing of a rivet in between the two riveting dies and through the rivet hole. In the first method the rivet is pushed through the rivet hole by the die 24 actuated by the air rams 11 and in the second method it is pushed through from the inside by the anvil die 21 actuated by the rams 12.

If desired, the relative positions of the hydraulic riveter and holder-on may be reversed, the former being inboard and the latter outboard. In practice, it has been found more convenient however to have them arranged as shown, as the bulky hydraulic bull riveter can be supported and moved more conveniently on the outside.

When it becomes necessary to move the apparatus past one of the bars or ribs of the ship's frame, the connecting bars 8 are withdrawn from the rivet holes of the plates and the two strongbacks moved past the said bar. The bars 8 are then passed through other rivet holes and the two plates connected and adjusted for the riveting of another section or area of the shell. It will be seen that the adjustment of the plates and the movement of the riveting devices is such that the plates may be riveted to the frame bars of the ship or to any other member of the ship's frame regardless of the thickness of the same or the length of the rivet employed. In fact the present apparatus can be adjusted and moved to any position necessary to do the work that is done by a yoke riveter during the original plating of the hull, and to do it at any time after the ship is completed and in commission.

An important feature of the improvements resides in the construction and arrangement whereby the hydraulic plunger and holder-on constituting the riveter proper are adjustable at all times and under all conditions so that the pressure of the riveter is not communicated to the shell or other part of the ship which is being riveted.

While the accompanying drawings are not

intended to be made to scale, it may be stated for the benefit of those skilled in the art and to enable them to practice the invention, that they represent the general proportions of an apparatus in actual use on a scale approximately three-fourths inch to the foot in Fig. 1 and one-half inch to the foot in Figs. 2 and 3, the bars, plates and some other parts being on a larger scale for better illustration.

10 It should be noted that whether the anvil die or the plunger die is applied to the headed end of the rivet, both members move against the rivet and toward each other in the squeezing operation, the head of the riveting plunger by the action of the hydraulic pressure backed by its strongback and the anvil by the pressure of its strongback communicated to it from the hydraulic riveter through the connecting bars. In this manner the hydraulic pressure in the riveter is caused to act on both ends of the rivet simultaneously.

It should also be noted that by the use of the apparatus described a very great increase in pressure in proportion to the weight of the backing is obtained.

What I claim is:

30 1. In an apparatus of the kind described, a fluid pressure device, a rivet holder-on and anvil device, the said two devices adapted to be positioned opposite each other and on opposite sides of a sheet metal shell composed of plates positioned to be riveted together and in position to engage and act against opposite ends of a rivet passed through said plates, backing means for said pressure device and said holder-on with respect to which they are mounted for lateral and vertical movement, and means extending through said shell for connecting said backing members and holding them against separating movement, whereby when the said pressure device is pressed against one end of a rivet and the said pressure is resisted by the said holder-on in contact with the opposite end of said rivet, the said backing devices will hold said pressure device and holder-on against yielding movement due to the connection of said backing devices through the shell, and whereby said pressure device and holder-on may be moved to engage opposite ends of rivets located at different parts of the shell without moving the said backing means or disconnecting them.

means of disconnecting them.

55 2. In a device of the character described, a riveter and an anvil adapted to be placed on opposite sides of plates to be riveted with a rivet to be squeezed between them, separate backing members for the said riveter and anvil with respect to which they are mounted to be laterally and vertically movable and members spacing and connecting said backing members, adapted to extend through said plates and located at points removed from the zone of operation of said riveter and anvil.

60

65

3. In an apparatus of the kind described, a hydraulic squeezing riveter and an anvil adapted to be placed on opposite sides of plates to be riveted, backing members or strongbacks against which the respective bases of said riveter and anvil are adapted to press, elongated connecting members adjustably secured to and connecting said strongbacks at points laterally removed from each other and adapted to pass through the plates, said connecting members adapted to secure said strongbacks in parallel planes and to adjust them with respect to said planes, whereby pressure against a rivet in the plates placed between the riveter and anvil will cause the anvil to move toward said riveter through pressure of the strongback of said anvil against it communicated in the form of a pull on said connecting members and last named strongback caused by the said riveter pressing against its strongback and the said backs are moved in unison and in a direction parallel to the line of riveting pressure, and pneumatically operated plungers connected with said backs and adapted to press against said plates to move the parts to riveting position and cause the riveter to pass a rivet in contact therewith through a plate.

4. In an apparatus of the kind described, a hydraulic squeezing riveter and an anvil adapted to be placed on opposite sides of plates to be riveted, backing members or strongbacks against which the respective bases of said riveter and anvil are adapted to press, elongated connecting members adjustably secured to and connecting said strongbacks at points laterally removed from each other and adapted to pass through the plates, said connecting members adapted to secure said strongbacks in parallel planes and to adjust them with respect to said planes, whereby pressure against a rivet in the plates placed between the riveter and anvil will cause the anvil to move toward said riveter through pressure of the strongback of said anvil against it communicated in the form of a pull on said connecting members and last named strongback caused by the said riveter pressing against its strongback and the said backs are moved in unison and in a direction parallel to the line of riveting pressure, and pneumatically operated plungers connected with said backs and adapted to press against said plates to move the parts to riveting position and cause the anvil to pass a rivet in contact therewith through a plate, and to position for riveting.

5. In an apparatus of the kind described, a hydraulic squeezing riveter and an anvil adapted to be placed on opposite sides of plates to be riveted, backing members or strongbacks against which the respective bases of said riveter and anvil are adapted to press, elongated connecting members adjustably secured to and connecting said strong- 130

backs at points laterally removed from each other and adapted to pass through the plates, said connecting members adapted to secure said strongbacks in parallel planes and to adjust them with respect to said planes, whereby pressure against a rivet in the plates placed between the riveter and anvil will cause the anvil to move toward said riveter through pressure of the strongback of said anvil against it communicated in the form of a pull on said connecting members and last named strongback caused by the said riveter pressing against its strongback and the said backs are moved in unison and in a direction parallel to the line of riveting pressure, and a stop carried by one of the connecting members and adjustable thereon and adapted to limit and gauge the movement of the backs with respect to the plates.

20 6. In an apparatus of the kind described, a hydraulic squeezing riveter and an anvil adapted to be placed on opposite sides of plates to be riveted, backing members or strongbacks against which the respective bases of said riveter and anvil are adapted to press, elongated connecting members adjustably secured to and connecting said strongbacks at points laterally removed from each other and adapted to pass through the plates, said connecting members adapted to secure said strongbacks in parallel planes and to adjust them with respect to said planes, whereby pressure against a rivet in the plates placed between the riveter and anvil will cause the anvil to move toward said riveter through pressure of the strongback of said anvil against it communicated in the form of a pull on said connecting members and last named strongback caused by the said riveter pressing against its strongback and the said backs are moved in unison and in a direction parallel to the line of riveting pressure, and the said riveter and anvil adapted to be moved to different positions vertically and laterally with respect to said backs.

Witness my hand this 8th day of April, 1930, county of New York, State of New York.

GEORGE H. BATES.
